UNITED STATES PATENT OFFICE.

FRANK A. HOILES, OF ALLIANCE, OHIO.

METHOD OF ORNAMENTING BRICKS.

1,154,118.

Specification of Letters Patent. Patented Sept. 21, 1915.

Application filed January 5, 1915. Serial No. 572.

To all whom it may concern:

Be it known that I, FRANK A. HOILES, a citizen of the United States, residing at Alliance, in the county of Stark and State 5 of Ohio, have invented certain new and useful Improvements in Methods for Ornamenting Bricks, of which the following is a specification.

This invention relates to the process of 10 ornamenting the face or faces of brick, and has for its object to render the process more efficient and of wide scope, so far as the ornamentation of the face or faces of the brick is concerned. This object, together 15 with other objects readily apparent to those skilled in the art, I attain by the construction illustrated in the accompanying drawings, although my invention may be embodied in other forms, the construction illus- 20 trated being chosen by way of example.

In the drawings:—Figure 1 is a view showing, in a conventional way, a die designed to shape the clay to be afterward cut, in any well known manner, into brick of the 25 desired size. Fig. 2 is a view illustrating, in a conventional way, the die and the devices for first plowing or roughening the surface, and second is employed for softening and making more yielding the surface 30 of the brick after it has been plowed or roughened. Fig. 3 is a sectional view showing two bricks in section and an ornamenting impression sheet placed in proper relative position. Fig. 4 is a view showing a 35 number of brick placed side by side and the ornamenting sheet placed upon the faces of the bricks. Figs. 5 and 6 are fragmentary views of ornamenting sheets designed to be placed in position to produce the proper and 40 desired ornamentation. Fig. 7 is a view showing the method of placing a number of brick upon a truck or other support and the proper position of a series of ornamenting sheets placed in proper position. Fig. 45 8 is a bottom plan view of the steam jet pipe. Fig. 9 is a fragmentary sectional view through the clay column.

Throughout the several views similar reference numerals indicate similar parts.

50 My improved process or method is carried out in substantially the following manner: The bar 1 is connected, in any convenient and well known manner, to the die 2, preferably by suitable clamping bolts. To the

bar 1 are attached the desired number of 55 plowing or furrowing pins 3 which pins are located in inclined positions with reference to the flow of clay, said pins being inclined downward for the purpose of better plowing or furrowing the flow of clay. For the purpose of regulating the depth of the furrows, the pins 3 are adjustably attached to the bar 1 by means of suitable set screws 4 or their equivalent.

For the purpose of softening and making 65 more plastic the clay upon the face, designed to be ornamented, I provide the pipe 5 to which pipe is attached the supply pipe 6, said supply pipe being for the purpose of conveying steam to the pipe 5, which steam 70 is delivered upon the face of the flow of clay, said steam passing through suitable apertures formed in the bottom or underside of the pipe 5.

It will be understood that by subjecting 75 the face of a flow of clay to a jet of steam that any loose particles of clay will be adhesively seated upon the body of clay. By subjecting the face of the flow of clay to a jet of steam, the plowed or roughened surface will be moistened, owing to the fact that while the clay is necessarily in a plastic state the steam will have a tendency to penetrate to a certain extent the body of the clay, 80 thereby making it more plastic and pliable. 85

In further carrying out my improved process the flow of clay, after it has been plowed and subjected to a jet of steam, is cut to produce the desired size of brick. After the bricks have thus been formed they 90 are hacked upon a truck, such as 7, the lower tier of brick being arranged to bring their faces designed to be ornamented upward. After the proper number of brick have been placed in position to produce the 95 lower tier of brick, the ornamenting sheet 8 is placed in the position illustrated in Fig. 4. This ornamenting sheet may be of many kinds and styles and of any material, such as wire gauze, paper or thin sheets. After 100 the ornamenting sheet 8 is placed in position the next, or second, tier of brick are placed with their to be ornamented faces placed downward so as to come in contact with the ornamenting sheet. The next, or third, tier 105 of brick are placed with their smooth or untreated faces downward and no ornamenting sheet placed between the second and

third tiers, but the remaining tiers are placed in the same position as the first and second tiers. This process or arrangement is carried out until the desired number of bricks are placed upon the truck or other foundation. By placing the ornamenting sheets in the position above described and just after subjecting the same to a jet of steam the surfaces of the brick coming in contact with the ornamenting sheets will be given the 10 configuration or ornamentation corresponding substantially with the form or ornamentation of the sheets, owing to the fact that the plastic material will be embedded or in other words the sheets will be embedded in the plastic material. It will also be understood that the sheets will also prevent the adjacent faces of the soft or plastic brick from adhering to each other.

20 It will be understood that the process to which this invention pertains has to do with the ornamentation or formation of the brick but in order to produce a brick after carrying out the above described process they 25 must be treated in the usual manner as to drying and burning, but such drying and burning does not enter into the present invention.

It will be understood that by placing the 30 ornamenting sheets, whether formed of metal or of any other material, between the tiers of brick they will prevent the brick from adhering to each other so that the brick can be easily removed and at the same 35 time prevent any injury by reason of the brick adhering to each other, thereby disfiguring the ornamentation.

Having fully described my invention what

I claim as new and desire to secure by Letters Patent is:

1. The method of ornamenting brick consisting of shaping the material into rectangular form, plowing the face into furrows, subjecting the furrowed face to a jet of steam, cutting the form into bricks and hacking the bricks while still moist with the furrowed faces adjacent each other and a separating sheet located between the furrowed faces of the bricks.

2. The method of ornamenting brick consisting in shaping the material into form, roughening the face of said form, subjecting said roughened face to a jet of steam, cutting said form into bricks after subjecting the same to a jet of steam, hacking said 55 bricks while still moist, placing a separating and ornamenting strip between tiers of bricks with their roughened faces adjacent each other.

3. The method of ornamenting brick consisting in shaping the material into form, roughening the face of said form, subjecting said roughened face to a jet of steam, cutting said form into bricks after subjecting the same to a jet of steam, hacking said 65 bricks while still moist, placing a separating and ornamenting strip between tiers of bricks with their roughened and steam treated faces adjacent each other.

In testimony that I claim the above, I 70 have hereunto subscribed my name in the presence of two witnesses.

FRANK A. HOILES.
